GRATER AND SHREDDER

Howard L. Threadgill and Ervin A. Williams,
Birmingham, Ala.

Application January 2, 1935, Serial No. 164

1 Claim. (Cl. 146—177)

This invention appertains to new and useful improvements in fruit comminuting devices and more particularly to a novel grater and shredder particularly adapted for domestic use.

5 An important object of the invention is to provide a compact and inexpensive grater and shredder of a portable nature.

Another important object of the invention is to provide a domestic type grater and shredder 10 wherein the object treating blades are quickly interchangeable.

These and various other important objects and advantages of the invention will become apparent to the reader of the following specification.

15 In the drawings:

Figure 1 represents a front elevational view of the device.

Figure 2 represents a rear elevational view of the device.

20 Figure 3 represents a vertical sectional view through the machine.

Figure 4 represents a fragmentary top plan view showing the coupling between the shafts and one of the smooth treating places.

25 Figure 5 represents a front elevational view of the grater wheel.

Figure 6 represents a fragmentary front elevational view of the shredder wheel.

30 Figure 7 represents a back elevational view of the grater wheel, the back of the shredder wheel being of the same construction.

Referring to the drawings wherein like numerals designate like parts, it can be seen that the combined device consists of the base 5 having 35 the narrow upright 6 merging into the relatively wide back wall 7. The short bottom wall 8 extends from one side of the back wall 7 and merges with a pair of relatively wide side walls 9—9, these side walls 9—9 each connected by the front wall 40 10, which at close intervals is provided with inwardly punched portions defining pointed abutments or protuberances 11.

45 Hingedly connected to the short bottom wall 8 is the closure 12 which operates between the lower edges of the side walls 9—9 and meets the lower edge of the front wall 10 as in the manner substantially shown in Figure 3.

50 A neck portion 13 rises from the upper portion of the back wall 7 and is provided at its upper end with the hand loop 14 whereby the machine can be very readily and conveniently carried.

The back wall 7 has an opening 15 therein through which the shaft 16 extends, this shaft being provided with a crank 17 and handle 18 at its outer end and with a lug 19 at its inner end. The stop collar 20 on the shaft limits inward 5 movement of the shaft 16, abutting the back side of the wall 7 in the manner shown in Figure 3 and being held in this position by the elongated strip spring 21 which is anchored at its lower end as at 22 while its upper end is slotted as at 23 to 10 receive the shaft 16.

The spring 21 thus holds the lug end of the shaft 16 in the slotted tubular socket 24 on the back side of the shredder wheel 25, which shredder wheel is provided with V-shaped cutting elements 26 on the front side thereof. The wheel 25 is thus held by the shaft against the front wall 19 as shown in Figure 3.

The grater wheel 27 is of the same construction as the shredder wheel 25 with the exception 20 that the projections on its working side are small projecting studs 28 to perform the necessary grating action in cooperation with the protuberances 11 on the front wall 10.

While the foregoing specification sets forth the 25 invention in specific terms, it is to be understood that numerous changes in the shape, size, materials may be resorted to without departing from the spirit and scope of the invention as claimed 30 hereinafter.

Having described the invention, what is claimed is:

A combination utensil of the character described comprising a receptacle, a shaft disposed 35 through one wall of the said receptacle, the opposite wall of the receptacle being provided with protuberances on the inner side thereof, a plate on the inner end of the shaft, having protuberances on the side thereof opposed to the wall 40 having protuberances, a fixed collar on the shaft outside of the receptacle, and a strip spring secured at one end to the receptacle and tensionally engaging the collar at its opposite end to urge the plate against the opposite wall of the receptacle, said strip spring being provided with an elongated slot therein for receiving the said shaft.

HOWARD L. THREADGILL.
ERVIN A. WILLIAMS.
